MEASURING SCOOP

Ethel M. Phillips, 134 Ramona Drive,
San Luis Obispo, Calif. 93401

Filed June 20, 1966, Ser. No. 2,732

Term of patent 3½ years

(Cl. D44—29)

FIG. 1 is a top plan view of a measuring scoop, showing my new design;

FIG. 2 is a side elevational view thereof;

FIG. 3 is a section taken on line 3—3 of FIG. 1 thereof, and

FIG. 4 is a perspective view of the same.

I claim:

The ornamental design for a measuring scoop, substantially as shown.
